(57) **CLAIM**

I claim the ornamental design for a portable canopy for electrical device, as shown and described.

DESCRIPTION

FIG. 1 is a front perspective view of a portable canopy for electrical device showing my ornamental design;

FIG. 2 is a rear perspective view thereof showing my ornamental design;

FIG. 3 is a left side view thereof showing my ornamental design;

FIG. 4 is a right side view thereof showing my ornamental design;

FIG. 5 is a bottom view thereof showing my ornamental design;

FIG. 6 is a top view thereof showing my ornamental design;

FIG. 7 is a rear view thereof showing my ornamental design;

FIG. 8 is a front view thereof showing my ornamental design.

FIG. 9 is an enlarged encircled portion view labeled "9" in FIG. 1;

FIG. 10 is an enlarged encircled portion view labeled "10" in FIG. 1;

FIG. 11 is an enlarged encircled portion view labeled "11" in FIG. 2; and,

FIG. 12 is an enlarged encircled portion view labeled "12" in FIG. 2.

The dash-dot broken lines are included to annotate partial views in FIGS. 1, 2 and 9-12 and form no part of the claimed design.
